LIGHT FIXTURE

George E. Eckert, Fort Atkinson, Wis., assignor to Thomas Industries Inc., Louisville, Ky., a corporation of Delaware

Filed Nov. 1, 1966, Ser. No. 4,503

Term of patent 7 years

(Cl. D48—3)

The dominant features of my design reside in the portions shown in full lines.

I claim:

The ornamental design for a light fixture, substantially as shown and described.
